PULVERIZING MACHINE

Austin A. Holbeck, Lakewood, and Halvor F. Holbeck, Cleveland, Ohio

Application October 29, 1932, Serial No. 640,204

1 Claim. (Cl. 83—11)

This invention relates to pulverizing apparatus and, as its principal object, aims to provide an improved pulverizing machine which is of very compact construction and which is very efficient in operation.

Another object of our invention is to provide an improved pulverizing machine, of the multiple zone type, wherein the pulverizing rotors are so arranged that the material is fed to the rotors in succession at the periphery thereof and passes through each rotor in opposition to centrifugal force.

A further object of our invention is to provide a pulverizing machine, of the multiple zone type, wherein the pulverizing rotor of each zone is in close running relation to one wall of the zone around a discharge opening therein, and is spaced from the other wall of the zone to provide a passage for feeding the material to be pulverized to the periphery of the rotor, whereby the material passes through the rotors in succession and passes through each rotor in opposition to centrifugal force.

The invention may be further briefly summarized as consisting in certain novel combinations and arrangements of parts, hereinafter described and particularly set out in the appended claim.

In the accompanying sheets of drawings,

Fig. 1 is a longitudinal sectional elevation of a pulverizing machine constructed according to our invention;

Fig. 2 is a transverse sectional view thereof taken substantially on line 2—2 of Fig. 1;

Fig. 3 is a longitudinal sectional view of another pulverizing machine embodying our invention; and

Fig. 4 is a transverse sectional view thereof taken substantially on line 4—4 of Fig. 3.

Detailed reference will now be made to the accompanying drawings illustrating preferred forms of the pulverizing apparatus of our invention. Before proceeding with such detailed description it should be understood, however, that our invention is not to be regarded as limited to the particular structural arrangements herein disclosed, but may be embodied in various other machines or apparatus.

In Figs. 1 and 2 of the drawings, we have shown our invention embodied in a pulverizing machine having a housing 10, which contains a plurality of grinding zones 11 and 12 and a fan 13 for causing a flow of air through the housing for moving the material to be pulverized through the grinding zones. The housing may be of any suitable form and is here shown as having a semi-

cylindrical top portion 14 and a squared bottom portion 15, the latter forming a suitable base upon which the machine is supported. The housing is provided at one end thereof with a removable cover 16, which forms the end wall of the housing, and which is provided with an inlet opening 17 for the material to be pulverized. At its opposite end the casing is provided with a chamber 18 in which the fan 13 is rotatably housed. This fan chamber is formed between the end wall 10 19 of the housing and a partition wall 20 which is spaced inwardly therefrom. The fan chamber is preferably of volute form and is provided with a substantially tangentially extending discharge nozzle 21 through which the mixture of air and pulverized material may be delivered from the machine.

The section of the housing which is located between the end wall 16 and the partition 20 constitutes the grinding compartment which contains the grinding zones 11 and 12. In forming these grinding zones, we provide a hollow cylindrical liner 21' which is mounted in the housing in coaxial relation with the shaft 22 upon which the fan 13 is mounted. This liner may be removably retained in the housing by the cover 16 and is preferably provided on its inner surface with teeth or corrugations 23 which assist in breaking up the material. A partition wall 24, preferably formed integral with the liner, divides the interior thereof into the two pulverizing zones 11 and 12 which are connected by a circular opening 25 located centrally of the partition wall. The grinding zone 12 is connected with the fan chamber 18 by means of a circular opening 26 located substantially centrally of the partition 20 and in substantial axial alignment with the opening 25 of the partition 24.

The fan shaft 22 extends through the openings 26 and 25 and is drivingly connected with pulverizing rotors 27 and 28 which rotate, respectively, in the grinding zones 11 and 12. The rotor 27 is provided with a hub 29, which is keyed or otherwise suitably connected to the shaft 22, and with a disk portion 30 which is disposed in close running relation with the partition 24. This disk portion is provided with a central opening 31, which aligns substantially with the opening 25 of the partition 24, and with a plurality of circumferentially spaced pulverizing or crushing elements 32. These crushing elements, which may also be referred to as impact or attrition elements, may be of any suitable form and are here shown as pegs formed integral with the disk portion 30 around the outer edge thereof and arranged to

extend toward the cover 16 substantially in the direction of the axis of the shaft 22.

For cooperation with the crushing elements of the rotor 27, we provide a circumferentially extending row of spaced crushing elements 33 which are preferably in the form of pegs arranged to extend toward the disk portion 30 of the rotor 27 just inwardly of the row of crushing elements 32. The stationary elements 33 extend around the 10 edge of a disk member 34 which may be supported in the housing in any suitable manner, such as by means of the brackets 35. This disk member is arranged in spaced relation to the cover 16 to form a passage for feeding the material from the 15 inlet 17 to the pulverizing rotor 27.

With the arrangement as just described, it will be seen that the material supplied to the housing through the inlet opening 17 is fed to the rotor 27 through annular space 36 which extends 20 around between the outer periphery of the rotor and the corrugated inner surface of the liner 21. The material entering this space is struck by the elements 32 and is thrown back and forth between these elements and the corrugated inner liner 25 which causes the material to be broken and crushed. If desired, the crushing action to which the material is subjected may be increased by enlarging some of the elements 32 to form hammers which extend outwardly in closer relation to the 30 corrugated inner liner, as shown in Fig. 2. The material passing inwardly through the spaces between the crushing elements 32 is subjected to a further crushing or grinding between the rotor 27 and the stationary crushing elements 33. 35 During the pulverizing action, a stream of air is drawn in, preferably through the inlet 17, by means of the fan 13. This stream of air flows inwardly through the rotor 27, causing the material to move inwardly in opposition to centrifugal force, with the result that only the fine particles 40 are drawn through the opening 25 with the air stream.

The pulverizing rotor 28 which rotates in the crushing zone 12, is provided with a hub 37' which 45 is keyed or otherwise secured to the shaft 22. This rotor is also provided with a disk portion 38 having at the outer edge thereof, a plurality of pulverizing or crushing elements in the form of circumferentially spaced pegs 39 which extend 50 axially of the housing around the discharge opening 26 of the partition 20. These elements overlap, and cooperate with, circumferentially spaced stationary crushing elements or pegs 40 which are mounted on this partition around the opening 26. 55 According to our invention, the disk portion 38 of this pulverizing rotor is spaced from the partition 24 to provide a substantially unobstructed passage 41 therebetween, which passage connects the discharge opening 25 of the zone 11 with an 60 annular space 42 extending around between the rotor 28 and the inner surface of the liner 21. The material delivered from the first grinding zone enters the annular space 42 through the passage 41 and from the annular space is fed inwardly into the second pulverizing rotor. The stream 65 of air, created by the fan 13, causes the material to flow through the passage 41 and into the annular passage 42 where the material is subjected to a further crushing action between the elements 70 39 and the corrugated inner surface of the liner. This flow of air also causes the material to move inwardly through the spaces between the crushing elements of the rotor, in opposition to centrifugal force, so that this material is subjected to a further crushing action by the cooperation of 75

the crushing elements of the rotor with the stationary crushing elements 40. By reason of the action of centrifugal force on the larger particles, only the finely pulverized material is drawn into the fan chamber through the opening 26. 5 This finely pulverized material is delivered from the machine, with the stream of air, through the delivery nozzle 21.

The fan 13 and the pulverizing rotors 27 and 28 may be actuated by any suitable means, for example, the shaft 22 may be conveniently driven by a suitable motor, such as the electric motor 43. If desired, the housing of the machine may be provided with a suitable bracket, such as the integral extension 44, which forms a convenient 15 mounting for the electric motor.

In crushing apparatus of this kind it is usually desirable that hard foreign bodies, such as tramp iron, be removed from the material to be crushed, so as to prevent injury to the pulverizing rotors 20 and liner and, to this end, we construct the housing of the machine with a pocket or chamber 45 outwardly of the liner 21, which pocket is connected with the lower end of the inlet opening 17 by means of the passage 46. The heavy foreign 23 particles entering the housing with the material to be pulverized, settle to the bottom of the inlet passage and find their way into the pocket 45 through the passage 46. The material thus collected in the pocket 45 may be removed, from 30 time to time, through a suitable opening provided in the housing for that purpose.

In Figs. 3 and 4 of the drawings, we have shown another pulverizing machine, which is constructed according to our invention, and which is provided with a housing 48 having pulverizing zones 49 and 50 therein and a fan chamber 51 from which the pulverized material is delivered through the tangential delivery nozzle 52. The housing is provided at one end thereof with a removable 40 cover 53 having an inlet opening 54, through which material to be pulverized may be fed, and through which air is drawn by rotation of the fan 55 in the fan chamber 51.

To form the pulverizing zones 49 and 50, we 45 provide the housing with a substantially cylindrical liner 56 having an integral partition wall 57 between the pulverizing zones. This liner may be retained in place in the housing by means of the removable cover 53. Pulverizing rotors 50 58 and 59 operate in the pulverizing zones 49 and 50, and are connected to a drive shaft 60, to which the fan 55 is also connected. This shaft extends longitudinally of the housing and may be driven by any suitable power means, such as 55 the electric motor 61. The partition wall 57 is provided with a central opening 62 around the shaft 60, which opening connects the pulverizing zone 49 with the pulverizing zone 50. A similar opening 63 is formed in the partition wall 64, 60 which is located between the pulverizing zone 50 and the fan chamber 51, such opening providing a discharge passage for the delivery of pulverized material from the pulverizing zone 50 to the fan chamber. 65

According to our invention, the pulverizing rotor 58 is disposed in close running relation to the partition 57 around the opening 62 provided in this partition. This rotor is preferably in the form of a hollow structure having spaced disk 70 and ring portions 65 and 66, and also having a plurality of circumferentially spaced axially extending crushing elements 67 disposed between these members at the outer edge thereof. The ring member 66 is in close running relation to the 75

partition 57 and is provided with a central opening 68 which registers with the opening 62 of the partition. The disk portion 65 is drivingly connected with the shaft 60 and is spaced from the cover 53 to provide a passage 69 for feeding the material to the rotor from the inlet opening 54. The material in the passage 69 is fed to the rotor through the annular space 70 extending between the crushing elements 74 and the corrugated inner surface 71 of the liner 56. The material entering this space is subjected to a crushing action between the element 74 and the liner until the material is rendered sufficiently fine to be drawn in through the rotor, in opposition to centrifugal force, by the flow of air created by the fan 55.

The pulverizing rotor 59, which operates in the pulverizing zone 50, is disposed in close running relation with the partition 64 so that the material which is delivered to the fan chamber through the passage 63 must first pass through this pulverizing rotor. The rotor itself comprises disk and ring portions 72 and 73, and a plurality of circumferentially spaced crushing elements 74 extending between the disk and ring portions around their outer edge. The ring portion 73 is in close running relation to the partition 64 and is provided with a central opening 75 which registers substantially with the opening 63 leading into the fan chamber. The disk portion 72 is drivingly connected with the shaft 60 and is spaced from the partition wall 57 to provide a passage 76 for feeding material to the rotor. As shown in Fig. 3, the passage 76 connects the opening 62 of the partition 57 with the annular space 71 extending around between the crushing elements 74 and the corrugated inner surface of the liner 56, so that material delivered from the pulverizing rotor 59 will be supplied to the pulverizing rotor 59. The material being supplied to the rotor 59 enters the annular space 71 and is subjected to a crushing action between the elements 74 and the corrugated liner, and when this material has been rendered sufficiently fine, it is drawn in through the spaces between the crushing elements 74, in opposition to centrifugal force, by the stream of air created by the fan. This finely pulverized material passes with the air stream into the fan chamber 51 through the opening 63 and is delivered from the fan chamber through the nozzle 52.

If desired, the liner 56 may be mounted in the housing in such a manner as to provide a space 78 therebetween for the collection of tramp metal or other hard foreign bodies. The pocket formed by the space 78 may be connected with the lower end of the inlet passage 69 by means of the laterally extending opening 79.

From the foregoing description and the accompanying drawings, it should now be readily understood that we have provided a compact and efficient form of pulverizing machine, which embodies a plurality of pulverizing zones and wherein the rotors of the pulverizing zones are so arranged that the material to be crushed

passes through the rotors in succession and passes through each rotor in opposition to centrifugal force. In the arrangement which we have provided, the passage of the material through each crushing zone in opposition to centrifugal force, results in the most efficient and thorough pulverizing action being obtained in each zone, since only the finely pulverized particles can be withdrawn from the pulverizing zones by the air stream. By thus providing a pulverizing machine wherein the most efficient pulverizing action obtainable is had in each pulverizing zone, we find that our invention may be embodied in a machine of relatively small size for a desired rate of output of pulverized material. Moreover, it will be seen that since the pulverizing zones of our improved machine function with maximum efficiency, a given output of pulverized material can be obtained with a smaller expenditure of power than has heretofore been possible in pulverizing machines.

While we have illustrated and described the pulverizing apparatus of our invention in a detailed manner, it should be understood, however, that we do not wish to be limited to the precise details of construction and arrangement of parts illustrated and described, but regard our invention as including such changes and modifications as do not involve a departure from the spirit of the invention and the scope of the appended claim.

Having thus described our invention, we claim:

In a pulverizing machine the combination of a housing having an end wall and an inlet adjacent thereto, a partition spaced from said wall and having an opening therein, a rotor in close running relation to said partition and having an opening registering substantially with the partition opening, said rotor also having a plurality of circumferentially spaced axially extending crushing elements rotatable about the partition opening, a member mounted in said housing and having circumferentially spaced axially extending crushing elements for cooperation with the crushing elements of said rotor, said member also having a disk portion spaced from said end wall to provide a passage for feeding material from said inlet to said rotor, a second partition in said housing spaced from the first partition and having a discharge opening therein, said second partition having a plurality of axially extending crushing elements spaced around the opening therein, a second rotor adjacent said second partition and having circumferentially spaced axially extending crushing elements for cooperation with the crushing elements of the second partition, said second rotor also having a disk portion spaced from the first mentioned partition to provide a passage for feeding material to such second rotor, and means for causing a flow of air through the housing whereby the material passes inwardly through the rotors in opposition to centrifugal force.

AUSTIN A. HOLBECK.
HALVOR F. HOLBECK. 65
